VAPOR ELECTRIC APPARATUS.

1,188,663.

Specification of Letters Patent. Patented June 27, 1916.

Application filed February 7, 1912. Serial No. 676,051.

To all whom it may concern:

Be it known that I, MAURICE AUGUSTE EUGÈNE LEBLANC, a citizen of the Republic of France, and resident of Paris, France, have made a new and useful Improvement in Vapor Electric Apparatus, of which the following is a specification.

This invention relates to vapor electric apparatus such for instance as mercury vapor lamps or rectifiers, in which both the anode and cathode are composed of conducting vaporizable material such as mercury, and has for its object to provide an improved construction of apparatus of this kind which shall be reliable and continuous in operation.

In vapor electric apparatus of the kind to which the invention relates it is well known that a large proportion of the total heat generated by the passage of the electric current when the device is operating, is evolved at the positive electrode or anode, and that the latter is therefore normally maintained at a higher temperature than the cathode. The evaporation of the mercury or other vaporizable material forming the electrodes is therefore greater at the anode than at the cathode, and the initial distribution of the mercury between the two electrodes gradually alters during the operation of the lamp, so that the amount of mercury at the cathode tends to increase with a corresponding diminution of the mercury at the anode. In order to restore the mercury thus collected at the cathode to the anode from time to time, various arrangements have heretofore been proposed, one of which consists in normally locating the cathode at a higher level than the anode, so that as soon as a predetermined amount of mercury has collected at the cathode any excess will flow under gravity along the container of the device to the anode, thereby maintaining the quantity of mercury of the two electrodes substantially constant. This method of attaining the desired result is, however, open to grave disadvantages inasmuch as the excess of mercury flowing from the cathode to the anode passes through the active vapor column of the device, and since the latter is at a comparatively high temperature, the mercury coming in contact with the hot column is more or less suddenly and violently vaporized, with a consequent increase

in the vapor pressure in the device, which often results in the extinction of the lamp due to the sudden change in its resistance characteristic.

According to the present invention the above disadvantages are avoided by the provision of improved means for automatically varying the evaporation of the mercury or other vaporizable material at the cathode of the device in accordance with the amount of liquid material collected at this electrode.

In order that the nature of the invention may be clearly understood reference may be made to the accompanying drawings, of which—

Figures 1, 2 and 3 are diagrammatic views illustrating a lamp constructed in accordance with the invention, the several figures showing various embodiments of the invention.

Referring now to Fig. 1, the negative electrode of the device is indicated at 1 as comprising a body of mercury or other vaporizable material located in a pocket 2 formed at one end of the container of the lamp, the lighting tube of the lamp containing the luminous vapor column being indicated at 3. The usual condensing chamber for controlling the resistance characteristic of the lamp is indicated at 4 as located immediately above the cathode 1 and a pocket 5 of suitable size and shape is formed in the container intermediate the lighting tube 3 of the lamp and the cathode 1. The positive electrodes or anodes are shown at 9, 9.

The operation of this form of the device is as follows: Assuming that the lamp is in operation and that the pocket 2 has become completely filled with mercury due to the lower temperature and therefore greater condensation at the cathode 1, any further condensation at the cathode will cause the excess of liquid thus formed to fall into the pocket 5 intermediate the cathode and the lighting tube, the pockets 2 and 5 being so formed that the excess of mercury enters the latter pocket in isolated globules so that the bodies of mercury in the two pockets 2 and 5 are never electrically connected with one another. The mercury in the intermediate pocket being small in amount relative to the mercury at the cathode, and being immediately adjacent to the hot vapor column of the device, is rapidly vaporized

so that any excess of mercury accumulating at the cathode end of the device is removed therefrom in the form of vapor without interfering with the proper operation of the apparatus.

Referring now to Fig. 2, an alternative construction is illustrated in which the cathode end of the container of the apparatus is provided with a special condensing chamber 6 located immediately above the cathode 1 and having its entrance 7 closely adjacent to the surface of the cathode. In operation this condensing chamber 6 is open to the vapor column of the apparatus through the passage 7 so long as the surface of the mercury forming the cathode 1 is below a predetermined level, and under these circumstances the condensing chamber 6 serves to cool the vapor column by radiation in the usual manner. As soon, however, as an abnormal quantity of mercury has accumulated at the cathode, due to condensation, the rise in level due to this condensation causes the surface of the mercury at the cathode 1 to seal the passage 7 leading to the condensing chamber 6, which is thereby rendered inoperative. The temperature at the cathode end of the apparatus therefore rises with a consequent increase in the evaporation from the surface of the cathode, thereby effecting a reduction in the amount of liquid mercury at this point. It will be readily understood that by the action above described the quantity of mercury at the cathode is maintained approximately constant.

Referring now to Fig. 3, a modification of the arrangement shown in Fig. 2 is illustrated, in which the apparatus is provided with the usual condensing chamber 4 in addition to the auxiliary condensing chamber 6 shown in the latter figure. The special condensing chamber 6 is in this case located on that side of the cathode 1 which is remote from the lighting tube 3 and is connected to the container by two passages 7 and 8, the lower, 8, of which constitutes a constantly open communication between the mercury of the electrode and the lower part of the auxiliary condensing chamber 6. The operation of this form of the apparatus is substantially the same as that already described with reference to Fig. 2, since any increase in the amount of mercury collecting at the cathode 1 will evidently seal the passage 7 leading to the condensing chamber 6 and thereby reduce the effective radiating area at the cathode end of the container of the device.

The arrangement above described may evidently be considerably modified in many respects and the invention is not to be regarded as restricted to the above described or other arrangement, except as indicated by the appended claims. Thus, for ex-

ample, the evaporation described herein may be applied either to the cathode or to the anode, as may be desired or found useful.

Having now described my invention, what I claim as new and desire to secure by Letters Patent is:—

1. In a vapor electric apparatus, positive and negative electrodes of conducting vaporizable material, means for isolating a portion of the vaporizable material at one of the electrodes and means for maintaining the portion thus isolated at a higher temperature than the remaining portion of the electrode.

2. In a vapor electric apparatus, positive and negative electrodes of conducting vaporizable material, means for isolating a portion of the vaporizable material at one of the electrodes, and providing the portion thus isolated with reduced facilities for radiation of heat.

3. In a vapor electric apparatus, positive and negative electrodes of conducting vaporizable material, a tube communicating with the said electrodes and means acting through the normal operation of the apparatus after starting for isolating a portion of the vaporized and condensed material at one electrode, such means consisting of a pocket or depression in close proximity to the negative electrode, capable of retaining a comparatively small portion of the material vaporized at the cathode, the pocket or depression when filled with vaporized material being on a level with the lower interior wall of the said tube.

4. In a vapor electric apparatus, positive and negative electrodes of conducting vaporizable material and means acting through the normal operation of the apparatus after starting for isolating a portion of the vaporizable material at the negative electrode, such means consisting of a depression close to the negative electrode chamber and located below the upper edge thereof and between the positive and negative electrodes of the apparatus.

5. In a vapor electric apparatus, positive and negative electrodes of conducting vaporizable material and means acting through the normal operation of the apparatus, after starting, for electrically insulating a portion of one of the electrodes under predetermined conditions during operation, such means consisting of a depression capable of retaining a comparatively small portion of the negative electrode and a barrier for shutting off the main portion of the negative electrode from external influences.

6. In a vapor electrode apparatus, positive and negative electrodes of conducting vaporizable material, a depression in close proximity to the negative electrode, acting through the normal operation of the apparatus, after starting, for receiving and iso-

lating a portion of the vaporized and condensed material at one of the electrodes and means for maintaining the portion thus isolated at a different temperature from the remaining portion of the electrode.

7. In a vapor electric apparatus comprising a container, positive and negative electrodes of conducting material therein, and a pocket formed in the container in close proximity to one of the electrodes and act-

ing through the normal operation of the apparatus, after starting, for receiving the excess of vaporized and condensed material from the adjacent electrode.

Signed at Paris, France, this twentieth 15
day of January, 1912.

MAURICE AUGUSTE EUGÈNE LEBLANC.
